UNITED STATES PATENT OFFICE.

MAX GRÜNING AND ARTHUR HENRY WOODFIELD, OF LUTON, ENGLAND.

HAT-LINING, BANDEAU, AND SIMILAR ARTICLE.

1,145,765.

Specification of Letters Patent. Patented July 6, 1915.

Application filed June 8, 1914. Serial No. 844,002.

To all whom it may concern:

Be it known that we, MAX GRÜNING, a citizen of the Swiss Republic, and residing at Guildford Buildings, Luton, Bedfordshire, 5 England, and ARTHUR HENRY WOODFIELD, a subject of the King of Great Britain and Ireland, and residing at 41 and 43 Guildford street, Luton, Bedfordshire, England, have jointly invented certain new and useful 10 Improvements in Hat-Linings, Bandeaux, and Similar Articles, of which the following is a specification.

This invention relates to bandeaux, hat-linings, and similar articles constituted by 15 flexible material distended between a hoop and a draw-string provided with means whereby the effective length and tension of the draw-string may be varied at will.

The object of the present invention is to 20 improve in various details, devices of the character specified, to the ends that such devices may be more readily fitted into hats and that hats fitted with such devices may be more efficiently ventilated than hitherto.

25 The invention consists in the novel features particularly explained and defined in the appended claims.

Reference is to be had to the accompanying drawings forming a part of this specification, in which similar characters of reference indicate corresponding parts in all 30 the views.

Figure 1 is a face view of a bandeau made 35 in accordance with this invention, a portion being broken away for the sake of clearness. Fig. 2 is a similar view showing an additional hoop; and Fig. 3 is a sectional side elevation showing the device combined with a hat-lining, a hat being indicated in dotted 40 lines.

Distended between a hoop *a* and a draw-string *b* is a flexible head portion composed of an inner annulus *c* of textile fabric such as velvet, velveteen, silk, or other supple and 45 appropriate fabric, and an outer annulus *d* of perforated material such as gauze, buckram, perforated celluloid or the like, but as shown net is the preferable material employed, said annuli being united at their 50 contiguous edges. The hoop *a* may be a solid wire hoop but, as shown, it is preferred to employ an adjustable expanding spring-hoop consisting of a length of spring-wire which has a constant tendency to expand or

assume the straight form, but is constrained 55 to preserve its annular shape by the fact of its end portions *e* and *f* overlapping and engaging one another; the end portion *e* being formed or provided at its extremity with an eye *g* which embraces and is adapted to 60 slide upon the end portion *f*, while the latter is similarly formed or provided with an eye *h* which in turn embraces and is adapted to slide upon the end portion *e*.

The hoop *a* is disposed in a pocket *j* at the 65 outer circumference of the annulus *d*, said pocket being preferably constituted between a double thickness of the net or other material of which the said annulus is made. When the hoop *a* is entirely free, its elasticity tends to cause the eyes *g*, *h* to slide toward one another until mutually arrested, in 70 which position of the eyes the hoop attains its greatest effective circumferential length, which may be made to correspond to complete distension of the outer annulus *d*.

The draw-string *b* is disposed in a pocket *k* formed at the inner circumference of the inner annulus *c* and serves for gathering-in 75 the circumference of the annulus *c*, and 80 yieldingly maintaining this inner circumference in the same plane as the outer circumference of the annulus *d*, and the end portions of said draw-string which is preferably of elastic cord are led out of the pocket *k* through an opening at the point *m* (preferably at the sear *n* whereat the ends of the fabric of the annulus *c* are united), and are tied or otherwise fastened together at 85 their extremities as indicated at *o*, so as to 90 prevent either end from becoming withdrawn within the pocket *k* in consequence of the initial tension to which said draw-string is subjected.

When it is desired to contract the outer 95 peripheral dimension of the bandeau, the eyes *g*, *h*, of the hoop *a* are slid apart from one another to the requisite distance, and the draw-string *b* is then drawn out through the opening at *m* until its effective length 100 has been so reduced that the tension to which it is subjected is sufficient to balance the expansive tendency of the hoop *a*; whereupon the exposed ends of the draw-string *b* are 105 tied together in a slip-knot as indicated at *p*. The pockets *j* and *k* will at the same time, obviously, become gathered or puckered up circumferentially, as indicated in

the drawings. By undoing the slip-knot *p* and letting-out (and afterward re-tying) the elastic draw-string *b*, the spring-hoop *a* may be allowed to expand to any desired extent up to the maximum limit of its effective circumferential length. It will also be evident that by drawing-up or letting-out the elastic draw-string *b*, the tension of the latter may be varied at will without affecting the circumferential length of the hoop *a*, this adjustment being capable of being made very readily at any time after the outer margin of the bandeau has been stitched into the hat.

15 Although an adjustable expanding spring-hoop has been described it is to be understood that the invention is not limited thereto and that a hoop of fixed circumferential length may be employed if the advantage of 20 adjustability is sacrificed.

If desired, a hoop *q* either of fixed circumferential length or an adjustable expanding spring-hoop such as the hoop *a* may be disposed in a pocket *r* at the outer circumference of the inner annulus *c*. This hoop *q* forms an abutment or bearing for the hat pins by which a hat is secured to the head of the wearer, such pins passing between the hoops *a* and *q* at each side of the 25 hat. The hoops *a* and *q* are preferably made of metal wire but cane or other similar material may be employed without departing from the spirit of this invention.

It is particularly to be observed that the 30 outer annulus of perforated or reticulated material insures thorough ventilation of the hat and such ventilation is insured without interfering with the various adjustments. Where the outer annulus *d* is composed of 35 perforated celluloid or the like the ends thereof must overlap and slide on one another when the various adjustments are made.

What we claim is:—

45 1. A bandeau for hats, comprising the combination of a hoop, a draw-string, and a flexible head portion distended between said hoop and said draw-string, said flexible head portion being composed partly of textile 50 fabric and partly of perforated material.

55 2. A bandeau for hats, comprising the combination of a hoop, a draw-string, and a flexible head portion distended between said hoop and said draw-string, said flexible head portion being composed of an inner annulus of textile fabric and an outer annulus of perforated material.

60 3. A bandeau for hats, comprising the combination of a hoop, a draw-string, a flexible head portion distended between said 65 hoop and said draw-string, said flexible head portion being composed of an annulus of textile fabric and an annulus of perforated material, and a hoop secured at the outer circumference of said annulus of textile fabric.

4. A bandeau for hats, comprising the combination of a freely expanding hoop, a draw-string, a flexible head portion distended between said hoop and said draw-string, said flexible head portion being composed of an inner annulus of textile fabric and an outer annulus of perforated material, and a freely expanding hoop secured at the outer circumference of said annulus of textile fabric. 75

5. A bandeau for hats, comprising the combination of a freely expanding spring-hoop, a draw-string, and a flexible head portion distended between said hoop and said draw-string, said spring-hoop being formed from a length of material the end portions of which overlap one another and are each bent to form an eye which embraces and is capable of sliding upon the other end portion. 80

6. A bandeau for hats, comprising the combination of a freely expanding spring-hoop, a draw-string, a flexible head portion distended between said hoop and said draw-string, said flexible head portion being composed of an inner annulus of textile fabric and an outer annulus of perforated material in the marginal edge of which the spring hoop is secured, and a second freely expanding hoop secured at the outer circumference 95 of said annulus of textile fabric. 90

7. A bandeau for hats, comprising the combination of a freely expanding spring-hoop, a draw-string, a flexible head portion distended between said hoop and said draw-string, said flexible head portion being composed of an inner annulus of textile fabric and an outer annulus of reticulated fabric, a pocket formed at the inner circumference of said annulus of textile fabric, in which pocket said draw-string is disposed, a pocket formed at the outer circumference of said annulus of textile fabric, a freely expanding spring hoop arranged in said second-named pocket, and a pocket formed at the outer circumference of said reticulated fabric, in which third-named pocket the first named expanding spring-hoop is disposed, said expanding spring-hoops being each formed from a length of material the end portions of which overlap one another and are each bent to form an eye which embraces and is capable of sliding upon the other end portion. 105 110 115

8. A bandeau for hats, comprising the combination of a freely expanding spring-hoop, a draw-string, a flexible head portion distended between said hoop and said draw-string, said flexible head portion being composed of an inner annulus of textile fabric and an outer annulus of reticulated fabric, a pocket formed at the inner circumference of said annulus of textile fabric, in which pocket said draw-string is disposed, a pocket formed at the outer circumference of said 120 125 130

annulus of textile fabric, a freely expanding hoop disposed in said second-named pocket, and a pocket formed at the outer circumference of said annulus of reticulated fabric, in which third-named pocket the first named expanding spring-hoop is disposed, said draw-string being formed from elastic cord the ends of which are brought out from said first-named pocket and are adapted to be tied together. 10
